UNITED STATES PATENT OFFICE.

JACOB EDSON, OF BOSTON, ASSIGNOR OF ONE-HALF TO EMILY L. CALDWELL, OF HYDE PARK, MASSACHUSETTS.

ROWLOCK.

SPECIFICATION forming part of Letters Patent No. 293,858, dated February 19, 1884.

Application filed June 18, 1883. (No model.)

To all whom it may concern:

Be it known that I, JACOB EDSON, a citizen of the United States, residing at Boston, in the county of Suffolk and State of Massachusetts, 5 have invented certain new and useful Improvements in Rowlocks; and I do hereby declare that the same are fully described in the following specification and illustrated in the accompanying drawings.

10 This invention relates to improvements in rowlocks, and it is carried out as follows, reference being had to the accompanying drawings, where—

15 Figure 1 represents a perspective view of the improved rowlock. Fig. 2 represents a vertical section thereof. Fig. 3 represents a vertical section at a right angle to the section shown in Fig. 2, and Fig. 4 represents a cross-section on the line A B, shown in Fig. 2.

20 Similar letters refer to similar parts wherever they occur on the different parts of the drawings.

a represents the forked upper end of the rowlock, in one piece with which is cast the 25 downwardly-projecting tapering shank a', as shown. In rowlocks of this kind the greatest amount of strain comes at the junction of the forked part a and its shank a', and to prevent its accidental breakage I cast in one piece 30 with it at this point a circular projection or collar, a'', which serves as a trunnion or journal, on which the rowlock turns in its bearing while in use, and on which the lateral strain is transferred while rowing. The rowlock is supported in a bearing-piece secured 35 to the rail of the boat, to which it is locked while in use, with freedom to turn around its axis, and from which it may easily be detachable when no longer required for use. The 40 said bearing-piece is composed of the plate b, which is let in in the upper part of the rail c, as shown, and secured firmly thereto by means of suitable fastening-screws, as usual. To the under side of the plate b is cast in one piece 45 the downwardly-projecting tapering sleeve b', having in its interior a cut-away portion or groove, b'', extending on one side from top to bottom of said sleeve, as shown. A corresponding side projection, a³, is made on the

shank a', by which means the said shank can 50 be put through the slotted sleeve b' when the forked piece a is held at a right angle, or nearly so, to the rail c, and prevented from being accidentally disconnected as soon as the rowlock is turned around its axis to the required 55 working position. By making the slot b'' extending throughout the entire length of the sleeve b', I am enabled to cast said bearing-piece without the need of a core, and thus cheapen the manufacture thereof considerably. 60 In one piece with the plate b is cast the annular bearing-ring b³, that is made to project above the plate b, as shown, its interior serving as a bearing for the collar a'' on the rowlock a. By making the annular bearing-ring 65 b³, as described, cast in one piece with the plate b, the latter is re-enforced and materially strengthened, besides permitting the use of an enlarged journal, a'', on the rowlock at the place where the greatest strain occurs in rowing. 70 The ring b³ is made somewhat larger in diameter than the width of the plate b, so as to form side projections, b⁴ b⁴, on said ring b³, projecting beyond the sides of said plate b, by which a very neat finish is obtained when the 75 plate b is let in and secured in place on its rail c, as shown. By having the enlarged collar a'' at the upper end of the shank a' the latter can be reduced in size, so that the same size shank may be used for different size 80 rowlocks, and consequently the same sockets or bearing-pieces may be used for different-size rowlocks, which is of great advantage in using long or short oars interchangeably, as occasion may require. The upper end of the 85 sleeve b' is made with a rounded edge corresponding to the rounded junction of collar a'', with shank a', as shown, by which great strength and freedom of action is obtained without liability of binding when in use. 90

Having thus fully described the nature, construction, and operation of my invention, I wish to secure by Letters Patent and claim—

1. The combination of the forked piece a, tapering shank a', enlarged collar a'', and locking projection a³, with the socket consisting of plate b, tapering sleeve b', having vertical groove b'', and upper annular bearing-

ring, b^3 , adapted to receive the collar a'' in a manner substantially as and for the purpose set forth.

2. The herein-described bearing-piece or socket for rowlocks, consisting of plate b , with its downwardly-projecting tapering sleeve b' , having internal vertical groove, b'' , in combination with upper annular bearing-ring, b^3 ,

all combined and arranged as and for the purpose set forth.

In testimony whereof I have affixed my signature in presence of two witnesses.

JACOB EDSON.
